(57) **CLAIM**

The ornamental design for a container cover, as shown and described.

DESCRIPTION

FIG. 1 is a top and side perspective view of my container cover according to a first embodiment of my new design and being shown in a closed position;

FIG. 2 is a bottom and side perspective view thereof;

FIG. 3 is a front elevation thereof;

FIG. 4 is a right side elevation view thereof, the left side elevation view being a mirror image thereof;

FIG. 5 is a top plan view thereof;

FIG. 6 is a bottom plan view thereof;

FIG. 7 is a top perspective view thereof showing the container cover in a partially open position;

FIG. 8 is a top and side perspective view of my container cover according to a second embodiment of my new design;

FIG. 9 is a bottom and side perspective view thereof;

FIG. 10 is a front side elevation thereof;

FIG. 11 is a right side elevation view thereof, the left side elevation view being a mirror image thereof;

FIG. 12 is a top plan view thereof;

FIG. 13 is a bottom plan view thereof; and,

FIG. 14 is a top perspective view thereof showing the container cover in a partially open position.

The even broken lines illustrate environmental structure and form no part of the claimed design.

1 Claim, 14 Drawing Sheets
